UNITED STATES PATENT OFFICE.

ALBERT B. COMBS AND FRANK A. BULLINGTON, OF PORTLAND, OREGON; SAID BULLINGTON ASSIGNOR OF ONE-HALF OF THE WHOLE RIGHT TO EARL G. SMITH, OF PORTLAND, OREGON.

CYLINDER-GRINDING MACHINE.

1,308,166.

Specification of Letters Patent.

Patented July 1, 1919.

Application filed January 25, 1917. Serial No. 144,451.

To all whom it may concern:

Be it known that we, ALBERT B. COMBS and FRANK A. BULLINGTON, citizens of the United States, residing in the city of Portland, county of Multnomah, and State of Oregon, have invented certain new and useful Improvements in Cylinder-Grinding Machines, of which the following is a specification.

10 Our invention relates to cylinder grinding machines, and more particularly to a machine adapted for grinding out the inside of engine cylinders, whereby to reform therein perfectly smooth and uniform inner surfaces, thus making such cylinders substantially as good as new. Our invention is also adapted to be mounted and adjusted for grinding the outside of pistons, whereby to make their outer surfaces perfectly 20 smooth and uniform, so that they will have a perfect fit within the cylinders.

The principal object of our invention is to provide an improved, automatic, power-driven machine of the character referred to, which can be quickly and accurately adjusted and centered for operation in a cylinder, or on a piston, and which will automatically operate a grinding element circumferentially around the inside of a cylinder, and through 30 the same longitudinally thereof, without any further attention.

Another object of our invention is to provide a machine of the character referred to, in which the grinding element, in addition to having a rotating movement and a movement longitudinally of its axis of rotation, has a variable revolving movement bodily about a center to one side of its axis of rotation, thus adapting said machine for grinding cylinders of various sizes with the same grinding element, together with means for simultaneously rotating the grinding element about its axis at one speed and for revolving the same bodily about an axis to 40 one side of its axis of rotation, at a different speed, and for feeding it longitudinally of its axis of rotation, in either direction, at a different and greatly reduced speed, all from one motor, or source of power.

45 Another object of our invention is to provide in a machine of the character referred to, means for locking said grinding element against its bodily revolving movement without interfering with the rotative movement

about its axis, whereby said machine can be 55 adapted for grinding pistons.

Other objects and advantages of our invention will be apparent from the following description of one practical embodiment thereof, taken with the accompanying sheets 60 of drawings in which—

Figure 1 is a side elevation of the invention;

Fig. 2 is a top plan view thereof;

Fig. 3 is an enlarged vertical sectional 65 view of the upper end of the machine, taken on the line 3—3 of Fig. 2;

Fig. 4 is a horizontal sectional view taken on the line 4—4 of Fig. 3;

Fig. 5 is a fragmentary, vertical, sectional 70 view taken on line 5—5 of Fig. 2;

Fig. 6 is a fragmentary, top, plan view, taken on line 6—6 of Fig. 1;

Fig. 7 is a top, plan view of our machine mounted in a horizontal position with the 75 piston grinder applied thereto;

Fig. 8 is a side elevation thereof;

Fig. 9 is an end view at line 9—9, Fig. 7;

Fig. 10 is an end view of the machine shown in Fig. 8, looking at the left hand 80 end thereof, with a part broken away to reduce the size of the figure;

Fig. 11 is a sectional view of a centering device for centering the cylinder grinding machine over a cylinder which is to be 85 ground; and

Fig. 12 is a bottom plan view thereof.

Referring now in detail to the drawings, Fig. 1, C designates a fragmentary, sectional view of a cylinder on which our machine is mounted for regrinding said cylinder. An open supporting frame, or block, 1, is mounted upon the cylinder and centered relative thereto, said frame comprising an upper ring 2, and a lower ring 3, 95 with center openings 4—4, in register with each other, as will be clearly understood from said Fig. 1.

Our machine proper is mounted upon this supporting frame, or block, 1, and comprises 100 a base, or supporting, casing 5, having on its under side an annular shoulder 6, adapted to fit into the central opening 4 of the upper ring 2, of the supporting frame 1. Formed as a part of said base casing 5, is a 105 bearing sleeve 7, having formed at one side a web, or lug, 8, to which is secured a guide bar 9. At the opposite side of said bearing

sleeve 7, said base casting has formed there-on a bearing box 10.

Slidably mounted through said bearing sleeve 7, is a cylindrical member 11, connected at its upper end with a cylindrical portion 12, of a main top casting 32, said cylindrical portion 12, having a guide lug 13, formed thereon, and slidably connected with the guide bar 9. Secured near the upper end around said cylindrical member 11, is a gear ring 14. This gear ring is secured to said cylindrical member 11, for driving the same, by means of a key 15, which key, however, may be moved downwardly in a seat 16, formed in the side of said cylindrical member 11, so as to permit said gear ring 14, to turn freely on said cylindrical member 11, as will be clearly understood from Figs. 1 and 5.

20 Mounted eccentrically through said cylindrical member 11, is a bearing tube 17, shown in section in Fig. 5. Mounted eccentrically within said bearing tube 17, is a spindle, or shaft, 18, upon the upper end of which is mounted a drive pulley 19, while at its lower end said spindle, or shaft, 18, is provided with a grinding element 20, which is detachable, and therefore can be exchanged for other grinding elements. In 25 Figs. 1 and 5, said bearing tube 17, is so turned within the bearing cylinder 11, that the shaft, or spindle, 18, is at an off center position within the cylindrical member 11. By turning the bearing tube 17, within the cylindrical member 11, said spindle, or shaft, 18, can be moved to a position concentric with said cylindrical member 11. This will be understood by the full line position, and the dotted line position of said spindle, 30 as shown in the plan view in Fig. 6.

Said spindle 18, has a tapered bearing member 17^a, Fig. 5, in the upper end of the tubular member 17, which is adapted to be raised and lowered in said tubular member 45 17, by means of a screw 17^b, which has a head flange 17^c, which fits into a notch in said tapered bearing 17^a, by means of which screw said tapered bearing 17^a, can be adjusted to take up wear, said screw 17^b, screwing into the top of the tubular member 17. It is to be understood, of course, that the tapered bearing member 17^a, around the upper end of the spindle 18, is a split bearing member.

50 55 In order to turn the bearing tube 17, within the cylindrical member 11, so as to vary the swing of the spindle 18, said bearing tube 17, is provided at its upper end with a plate 21, provided with a circular slot 22, 60 therein, adapted to receive a screw bolt 23, for locking said plate and said bearing tube 17, in varied adjusted positions, within the cylindrical member 11. The cylindrical member 11, is also provided around its upper end with a ring or plate.

Rotatably seated at its lower end in the bearing box 10, is a main feed screw 25. Mounted on said screw near its upper end is a threaded sleeve, or long feed nut, 26, shown in section in Fig. 3, keyed to which 70 is a gear 27. Mounted to turn loosely on said feed nut 26, and one above the other, are two compound gears 28 and 29, each of which has a pinion portion designated, respectively 28^a and 29^a. Also mounted on said feed nut 75 26, above the gear 29, is a beveled gear 30, which is keyed to said sleeve 26, as at 31. The upper end of said feed nut 26, has a bearing in the main top casting 32. Mounted in a portion 32^a, of said main top casting 80 is a short shaft 33, provided on its outer end with a hand wheel 34, having a handle 35. On its inner end said shaft 33, is provided with a gear 36, which meshes with the beveled gear 30, keyed to the sleeve 26. Thus 85 by operating the hand wheel 34, the feed nut 26, can be rotated through the beveled gears 30 and 36, causing said sleeve 26, to move upon the screw 25, in either direction, as desired.

90 Mounted in a bearing portion 32^b, of said top casting 32, is a driving shaft 37, provided near its upper end with a driving pulley 38. Slidably mounted upon the upper end, and keyed to said shaft 37, is clutch 95 member 39, adapted to be moved by hand into and out of interlocking engagement with the pulley 38, said clutch member being provided with a plurality of pins 39^a, adapted to be moved into sockets 38^a, in said 100 pulley 38. Said clutch member is frictionally held out of engagement with said pulley 38, by means of a spring-pressed ball 40, as clearly shown in Fig. 3. Mounted upon said driving shaft 37, is a pinion 41, which is 105 keyed to said shaft by means of a pin 42. Said pinion 41, meshes with the gear 29, on the threaded sleeve or long feed nut 26, which moves on the screw 25. Loosely mounted on the shaft 37, is a compound gear 43, which meshes with the pinion portion 29^a, of the gear 29, the pinion portion 43^a, of said compound gear 43, meshing with the gear 28. Also mounted loosely 110 on said shaft 37, is a second compound gear 44, which meshes with the pinion portion 28^a, of the gear 28. The pinion portion 44^a, of the gear 44, constitutes the driving pinion for a group of pinions 45, 46 and 47, mounted upon a supporting member 48, on said 115 shaft 37, and provided with a handle 49, whereby said supporting member 48, can be turned on said shaft 37, to put either pinion 45, or pinion 47, into mesh with the gear 27, which is keyed to the threaded sleeve or nut 26, as at 27'. By moving pinion 47, into mesh with said gear 27, said gears 27, is driven in one direction, and by moving the pinion 45, into mesh with said gear 27, said gear 27, is reversed and 120 125 130

driven in the opposite direction from the pinion portion 44^a, of the gear 44. Thus by movement of the handle 49, in either direction, the threaded sleeve, or feed nut 26, 5 can be driven in either direction from the shaft 37, through the train of gears above described, as will be clearly understood from Figs. 3 and 4. Mounted upon the lower end of said shaft 37, is a fan element 50, 10 turning within a hopper-like member 51, provided with a pipe, or tube, 52, which extends downwardly into a position to blow the grindings and dust from the grinding element 20, and the upper end of the 15 cylinder C, downwardly, into said cylinder C. Supported by the top casting 32, is a motor 53, the drive shaft 54 of which is provided with a driving pulley 55. Pivoted connected to the end of the top casting 32, 20 is a lever 56, upon one end of which is mounted a pulley 57, and the other end of which lever is connected by means of a spring 58, to the body portion of said top casting 32. A belt 59, extends around said 25 pulley 57, and partially around the pulley 55, of the motor, around the pulley 38, on the drive shaft 37, and around the pulley 19, on the driving spindle 18, and thence back to the pulley 57. The spring-controlled 30 lever 56, which carries the pulley 57, operates automatically to keep the driving belt 59 taut.

Thus from the motor 53, the shaft 37, which carries the pulley 38, and the grinding spindle 18, which carries the pulley 19, are directly driven at a high rate of speed. From the shaft 37, and its pinion 41, secured thereto, through the train of gears above described, said threaded sleeve, or feed nut, 26, 40 is driven at a greatly reduced speed for moving said feed nut, and the main top casting 32, which carries the cylinder member 11, the tubular member 17, and the grinding spindle 18, gradually downwardly, through 45 the bearing sleeve portion 7, of the base casting 5, thus providing for the feeding of the grinding element 20, longitudinally through the cylinder C, during its revolving movement and its rotative movement. The gear 50 ring 14, on the cylindrical member 11, is in mesh with the gear 28, of said train of gears and is thus driven at a less speed than is the shaft 37, and the spindle 18, and at a greater speed than is the long feed nut 26. Through 55 this drive, between the gear 14 and the gear 28, the cylindrical member 11 is driven, revolving the tubular member 17, and the spindle 18, in such a way that the grinding element 20, on the lower end of the spindle 60 is carried bodily around the inner wall of the cylinder C, during its rotating movement, and its feed movement longitudinally through said cylinder.

As before described, the turning of the 65 tubular member 17, to different positions

within the cylindrical member 11, regulates the throw or circular course of travel of said spindle and its driving element 20, thus making it possible to regulate the travel of said grinding element so as to adapt it to cylinders of different diameters. By changing 70 said grinding element for grinding elements of different diameters, a still further adaptation of said machine can be made for smaller or larger cylinders. 75

Referring to Figs. 11 and 12, I will now describe the mechanism for adjusting the machine centrally over the cylinder C. The supporting frame 1, is placed on the top of the cylinder C. A centering device is then 80 placed in the supporting frame 1, which centering device comprises a round body casting 60, adapted to fit the central opening in the lower ring 3, of said open frame 1, as clearly shown in said Fig. 11. Mounted 85 on the under side of said round body member 60, of said centering device, is a series of depending supporting lugs 61—61, pivotally connected to each of which is a bell crank lever 62, one end of which is adapted 90 to be swung outwardly against the inside of the cylinder C, while their other ends, or arms, approach each other, as at 63, Fig. 11, in a position to be engaged by the lower end of a screw 64, provided at its upper end 95 with an operating member 65, whereby as said screw 64, is turned down through the body 60, it presses downwardly on the inner ends of said bell crank levers 62, forcing their lower arms outwardly together into 100 bearing engagement with the inner wall of said cylinder C. This adjustment moves the frame 1, so that the central openings 4—4 in the open frame 1, is centered relative to the inside of the cylinder C. In this position 105 said open frame 1, is firmly clamped onto the cylinder C, in any desired manner, after which the centering device 60, can be removed and the grinding machine set thereupon, with its base plate 5, seated in the 110 top ring 2, of said open frame 1, as clearly shown in Fig. 1.

Referring now to Figs. 7, 8, 9 and 10, we will describe our invention as adapted for grinding pistons. A horizontal base 66, 115 having a vertical wall member 67, with a central opening 67^a therethrough, is provided, said base having an extension 68, upon which is slidably mounted a tail-stock 69, having the spindle 70, with operating 120 hand wheel 71, and the center pin 72, adapted to be set at the center of a piston P. The base plate 5, of the machine, is inserted into the opening 67^a, in said vertical wall member 67, with the ends of the cylindrical 125 member 11, the bearing tube 17, and the spindle 18, projecting therethrough, with the grinding element 20, in position to move against the side of the piston P, as clearly seen in Figs. 7 and 8. The guide bar 9, at 130

its upper end, is supported upon a block 73, at one end of the base 66, said guide bar 9 thus forming a track, or support, upon which the guide lug portion 13, of the main top 5 casing of the machine moves. Mounted upon the base 66, at one side, is a standard 74, provided at its upper end with a bearing box 75, to receive a shaft 76, which is supported at its opposite end in a similar bearing box 77, formed as a part of the wall member 67, as will be understood from Fig. 7. Secured to said shaft 76, is a gear drum 78, so positioned that it will mesh with the gear ring 14. On the cylindrical member 15 11, the opposite end of said shaft 76, is provided with a holding block, or chock, 79, adapted to receive and hold and turn the piston P.

When our machine is thus used for grinding a piston, it will be evident that the revolving movement of the cylindrical member 11, is not necessary. Therefore the key 15, which locks the gear ring 14, to said cylindrical member 11, is withdrawn so as to permit said gear ring to turn upon said cylindrical member 11, as in Fig. 8.

In order to prevent said cylindrical member 11 from turning, a set screw 80, is provided in the bearing casting 12, of the main 30 top casting 32, whereby to secure said cylindrical member 11, against turning during the operation of the machine. As the machine is thus operated, the spindle 18, is driven or rotated about its axis and is fed 35 longitudinally because of the drive from the shaft 37, through the train of gears to the threaded sleeve, or feed nut, 26, the grinding element 20, revolving at a high rate of speed and moving longitudinally along the 40 piston P, said piston P being revolved through its shaft 76, running loose on the cylindrical member 11, and driven from the gear 28.

Attention is called to the fact that from 45 one motor, or source of power, all of the necessary driving connections are made for driving the power shaft and the grinding element at a high rate of speed, and for feeding said grinding element slowly longitudinally through a cylinder, or along a piston, with means for revolving said grinding element bodily around the inside of a cylinder, as hereinbefore described, together with means for locking said cylindrical 50 member 11, whereby to prevent the bodily revolving movement of said grinding element when said machine is used for grinding a piston, as described.

We are aware that many changes can be 60 made in our invention as here embodied for purposes of illustration, without departing from the spirit thereof, and we do not, therefore, limit the invention to these details, except as we may be limited by the hereto 65 appended claims.

We claim:

1. In a grinding machine of the character referred to, in combination, a cylindrical member rotatably and movably mounted, a tubular bearing member rotatably mounted 70 eccentrically in said cylindrical member, a driving shaft rotatably mounted eccentrically through said tubular bearing member and provided at its end with a grinding element, said driving shaft having its bearings 75 in said tubular bearing member, a motor, and driving connections from said motor for simultaneously rotating said cylindrical member and said driving-shaft at different speeds and for automatically moving said 80 cylindrical member and said driving shaft longitudinally at a greatly reduced speed.

2. In a grinding machine of the character referred to, in combination, a cylindrical member rotatably and movably mounted, a 85 tubular bearing member rotatably mounted eccentrically in said cylindrical member, a driving shaft rotatably mounted eccentrically through said tubular bearing member and provided at its end with a grinding element, a motor, driving connections from said motor for simultaneously rotating said cylindrical member and said driving shaft at different speeds, and for automatically moving said 90 cylindrical member and said driving shaft longitudinally at a greatly reduced speed, and means for reversing, at will, the direction of the longitudinal movement of said cylindrical member and driving shaft.

3. In a grinding machine of the character referred to, in combination, a cylindrical member rotatably and movably mounted, a tubular bearing member rotatably mounted eccentrically in said cylindrical member, a 105 driving shaft rotatably mounted eccentrically through said tubular bearing member and provided at its end with a grinding element, said driving shaft having its bearings in said tubular bearing member, a motor, 110 driving connections from said motor for simultaneously rotating said cylindrical member and said driving shaft at different speeds and for automatically moving said cylindrical member and said driving shaft longitudinally at a greatly reduced speed, and means for manually moving said cylindrical member and said driving shaft longitudinally, in either direction, at will.

4. In a grinding machine of the character referred to, in combination, a cylindrical member rotatably and movably mounted, a tubular bearing member rotatably mounted eccentrically in said cylindrical member, a driving shaft rotatably mounted eccentrically through said tubular bearing member and provided at its end with a grinding element, a motor, driving connections from said motor for simultaneously rotating said cylindrical member and said driving shaft at 130

- different speeds and for automatically moving said cylindrical member and said driving shaft longitudinally at a greatly reduced speed, means for reversing, at will, the direction of the longitudinal movement of said cylindrical member and driving shaft, and means for manually moving said cylindrical member and said driving shaft longitudinally, in either direction, at will.

5 10. 5. In a grinding machine of the character referred to, in combination, supporting means, a cylindrical member rotatably and movably mounted therein, a tubular bearing member adjustably mounted eccentrically in said cylindrical member, a grinding shaft rotatably mounted eccentrically through said tubular bearing member, said grinding shaft having bearings in said tubular bearing member, a grinding element thereon, a power shaft, a motor, driving connections therefrom to said power shaft and to said grinding shaft, gear connections from said power shaft to said cylindrical member for turning the same, and means driven from said power shaft for moving said cylindrical member and said grinding shaft longitudinally, substantially as described.

15 20. 6. In a grinding machine of the character referred to, in combination, supporting means, a cylindrical member rotatably and movably mounted therein, a tubular bearing member adjustably mounted eccentrically in said cylindrical member, a grinding shaft rotatably mounted eccentrically through said tubular bearing member, a grinding element thereon, a power shaft, a motor, driving connections therefrom to said power shaft and to said grinding shaft, gear connections from said power shaft to said cylindrical member for turning the same, and means driven from said power shaft for moving said cylindrical member and said grinding shaft longitudinally, substantially as described.

25 30. 7. In a grinding machine, in combination, supporting means, a cylindrical member mounted to be rotated and moved longitudinally therein, a tubular bearing member mounted eccentrically in said cylindrical member, a grinding shaft rotatably mounted eccentrically through said tubular bearing member, a grinding element thereon, a power shaft, a motor, driving connections therefrom to said power shaft and to said grinding shaft, gear connections from said power shaft to said cylindrical member for turning the same, and means driven from said power shaft for moving said cylindrical member and said grinding shaft longitudinally, said means being reversible at will, whereby to move said member and said shaft in either direction, substantially as described.

35 40. 8. In a grinding machine, in combination, supporting means, a cylindrical member mounted to be rotated and moved longitudinally therein, a tubular bearing member mounted eccentrically in said cylindrical member, a grinding shaft rotatably mounted eccentrically through said tubular bearing member, a grinding element thereon, a power shaft, a motor, driving connections therefrom to said power shaft and to said grinding shaft, whereby to reverse the direction of movement longitudinally of said cylindrical member, a motor, and driving connections therefrom to said power shaft and to said grinding shaft, whereby said power shaft and said grinding shaft are driven direct from said motor, and said cylindrical member is revolved at a reduced speed from the gear connections from said power shaft and is moved longitudinally by said screw and its connections, substantially as described.

45 50. 9. In a grinding machine, in combination, supporting means, a cylindrical member mounted to be rotated and moved longitudinally therein, a tubular bearing member mounted eccentrically in said cylindrical member, a grinding shaft rotatably mounted eccentrically through said tubular bearing member, a grinding element thereon, a power shaft, a motor, driving connections therefrom to said power shaft and to said grinding shaft, whereby said power shaft and said grinding shaft are driven direct from said motor, and said cylindrical member is revolved at a reduced speed from the gear connections from said power shaft and is moved longitudinally by said screw and its connections, substantially as described.

55 60. 10. In a grinding machine, in combination, a supporting base, provided with a driving shaft having means for holding and revolving a piston, a grinding mechanism adapted to be mounted on said base and comprising a cylindrical member mounted to be moved longitudinally, a grinding shaft rotatably mounted through said cylindrical member, a motor, driving connections from said motor for driving said grinding shaft and for moving said cylindrical member longitudinally, and driving connections to said driving shaft, whereby said driving shaft and said grinding shaft are rotated and said cylindrical member and said grind-

65 70. 75. 80. 85. 90. 95. 100. 105. 110. 115. 120. 125. 130.

ing shaft therein are moved longitudinally, substantially as described.

11. In a grinding machine, in combination, a supporting base provided with means for rotatably supporting a piston, a grinding mechanism adapted to be imputed on said base and comprising in combination a grinding shaft mounted to be adjusted bodily about an axis parallel and eccentric 5 to its axis of rotation and to be revolved and moved longitudinally, a motor, driving connections from said motor for revolving said grinding shaft and said piston supporting means and for moving said grinding 10 shaft longitudinally, and a grinding element 15 on said grinding shaft, substantially as described.

12. In a grinding machine, in combination, a supporting base, a driving shaft provided with means for supporting and revolving a piston, a cylindrical member mounted to be revolved and to be moved longitudinally therein, a grinding shaft rotatably and adjustably mounted eccentrically 25 therein, a grinding element thereon, a motor, driving connections therefrom for driving said driving shaft and said grinding shaft and for moving said cylindrical member and said grinding shaft longitudinally, substantially as described.

13. A grinding machine comprising in combination a supporting base provided with a driving shaft having means for supporting and turning an article to be ground, a grinding mechanism adapted to be detachably mounted thereupon and comprising in combination a cylindrical member, a tubular bearing member mounted eccentrically and adjustably therein, a grinding shaft 30 mounted eccentrically through said tubular bearing member and provided with a grinding element adjacent the article to be ground, a motor, driving connections therefrom to said grinding shaft, a screw with 35 feed nut thereon, gears on said feed nut, connections from said feed nut to said cylindrical member, a gear ring on said cylindrical member in mesh with the gears on said feed nut, driving connections from said motor to 40 said gears, whereby to turn said feed nut on said screw and to rotate said cylindrical member, means for locking said cylindrical member against rotation at will without interfering with its movement longitudinally, and driving 45 connections to said driving shaft, substantially as shown and described.

14. A grinding machine comprising in combination a supporting base provided with a driving shaft having means for supporting and turning an article to be ground, a grinding mechanism adapted to be detachably mounted thereupon and comprising in combination a cylindrical member, a tubular bearing member mounted eccentrically 50 and adjustably therein, a grinding shaft 55 and driving connections to said driving shaft, substantially as shown and described.

15. A grinding machine comprising in combination a supporting base provided with a driving shaft having means for supporting and turning an article to be ground, a grinding mechanism adapted to be detachably mounted thereupon and comprising in combination a cylindrical member, a tubular bearing member mounted eccentrically and adjustably therein, a grinding shaft mounted eccentrically through said tubular bearing member, a screw with a feed nut, gears mounted on said feed nut, driving connections to said driving shaft, substantially as shown and described.

16. In a grinding machine, in combination, a supporting base a driving shaft provided with a gear drum and means for supporting and turning an article to be ground, a grinding mechanism adapted to be mounted on said supporting base and comprising a cylindrical member provided with a gear ring adapted to mesh with said gear drum, means for locking said gear ring to said cylindrical member at will, a bearing tube mounted eccentrically within said cylindrical member, means for adjusting the same, a grinding shaft mounted eccentrically within said tubular bearing member, a screw provided with a feed nut, gears mounted on said feed nut, a power shaft provided with gears adapted to mesh with the gears on said

driving shaft, substantially as shown and described.

17. In a grinding machine, in combination, a supporting base a driving shaft provided with a gear drum and means for supporting and turning an article to be ground, a grinding mechanism adapted to be mounted on said supporting base and comprising a cylindrical member provided with a gear ring adapted to mesh with said gear drum, means for locking said gear ring to said cylindrical member at will, a bearing tube mounted eccentrically within said cylindrical member, means for adjusting the same, a grinding shaft mounted eccentrically within said tubular bearing member, a screw provided with a feed nut, gears mounted on said feed nut, a power shaft provided with gears adapted to mesh with the gears on said

feed nut, a motor, driving connections from said motor to said power shaft and to said grinding shaft, gear connections from said power shaft to said feed nut and to said 5 gear ring on said cylindrical member, whereby to turn said feed nut and said cylindrical member, means for reversing the direction of drive of said nut at will, means for manually turning said feed nut, and a clutch 10 mechanism for disconnecting the drive from

said motor to said power shaft, substantially as described.

Signed at Portland, Multnomah county, Oregon, this 19th day of January, 1917.

ALBERT B. COMBS.

FRANK A. BULLINGTON.

In presence of—

I. M. GRIFFIN,

WARREN P. SMITH.
